SIDE BEARING FOR RAILWAY CARS

Charles De Los Rice, West Hartford, Conn.

Application April 30, 1934, Serial No. 723,025

3 Claims. (Cl. 308—226)

This invention relates to improvements in side bearings, such as are used for supporting the body of a railway car upon a truck to which the body is pivotally secured, and has as its object 5 a side bearing of the class described which will allow for free pivotal and vibrational movements between the truck and the car body without imposing wear or undue strain upon the side bearing.

10 A further object resides in the provision of a side bearing of the character described which will support the car body for substantially frictionless vibrational motion sidewise relative to the truck, the construction and arrangement being such 15 that the wearing of flat surfaces upon the bearing roll is avoided, the flanges of the car wheels may readily adjust themselves against the rails with the least possible resistance thus adding to the life of the car wheels and rails, and the riding qualities of the car body are improved.

20 A still further object resides in the provision of a side bearing of the character described which is simple and economical to manufacture and assemble, which is of rugged construction so that 25 it is not likely to get out of order and become broken, and which may be maintained in proper lubricated condition.

Other objects will be in part obvious and in part pointed out more in detail hereinafter.

30 The invention accordingly consists in the features of construction, combination of elements and arrangement of parts which will be exemplified in the construction hereinafter set forth and the scope of the application of which will be 35 indicated in the appended claims.

In the accompanying drawings, wherein I have shown, for illustrative purposes, one embodiment which the present invention may take:

Figure 1 is an elevational view of a fragmentary 40 portion of a car body and one of its associated trucks and shows the device of the invention as applied between the body and truck;

Fig. 2 is a view of my improved side bearing on an enlarged scale, shown partly in side elevation and partly in section, to better illustrate 45 the construction thereof;

Fig. 3 is an end elevation of my improved side bearing, a portion thereof being broken away to better illustrate the construction thereof;

50 Fig. 4 is a transverse vertical sectional view on the line 4—4 of Fig. 2; and

Fig. 5 is a diagrammatic view of the under side of the cradle support showing the three supporting bosses and the bolt openings.

55 Referring to the drawings in detail, the numeral

10 indicates generally one of the bolster members of a truck frame. The truck frame may be supported in any suitable manner by the wheeled axles. By way of illustration only, I have shown one type of spring suspension which may be employed. Referring to Fig. 1, 12 designates one of the wheels and 14 the axle to which the wheel is secured. Upon the end of the axle is a journal box 15. A spring 18 is supported at its central portion upon the top of the journal box, and has 10 each of its ends flexibly connected by means of a link 20 to a respective hook bracket 22 secured to the bolster member 10. It will be understood that the car body is pivotally connected to the truck in any suitable manner so as to permit the 15 car to pass around curves. This pivotal connection, so far as the present invention is concerned, may take any suitable form or type. I have shown for illustrative purposes, more or less diagrammatically, a pivot pin 25 which depends from the 20 bottom of the car body 9 and which has a vertical bearing on the truck frame, the bearing not being illustrated. This pivotal connection may have the construction and arrangement disclosed in my copending application Serial Number 25 707,203, filed January 18th, 1934. The side bearings are suitably positioned with respect to the pivot pin 25, the position and number of the bearings depending upon requirements. Where 30 the truck supports the end of only one car, there may be two side bearings disposed to opposite sides of the pivotal connection between the car and the truck, and where the adjacent ends of two cars are pivotally supported upon a single truck, there 35 may be provided four side bearings upon the truck, two for each car end, as disclosed in my copending application Serial Number 707,200, filed January 18th, 1934. In any event, the arrangement is such that the car body may pivot 40 with respect to the truck and the pivotal connection between the car body and truck will closely control or limit vibratory sidewise motion of the car body.

In accordance with the present illustrative disclosure of the present invention, my improved side bearing comprises four main elements, namely, a track member 42 secured to the underside of a car body, a cradle support secured to the truck frame, a roll cradle mounted in said support for oscillatory movement about a horizontal axis extending generally in the direction of the length of said track member, and a roll 40 supported in said cradle for rotary or turning movement about an axis disposed at right angles to the 50

axis about which said cradle is adapted to oscillate.

The track member 42 has on its underside a groove or trackway 137 which is preferably curved 5 in the direction of its length about the axis about which the truck is adapted to pivot, namely, about the axis of the pivot pin 25. This groove or trackway is transversely curved, as shown most clearly in Figs. 3 and 4. The track member may 10 be secured to the car in any suitable way. I have shown a pair of transversely disposed I-beams 27 and 28 on the underside of the car frame, and riveted, or otherwise suitably connected, to the underside of these beams is an anchor plate 30. 15 The top surface of the track member engages against the bottom of this anchor plate. The track member is secured in place by screws 130 which extend through reinforcing members 132 and the anchor plate 30. The reinforcing members, which are on the top of the plate 30, are 20 in the form of hollow square bars within which are cylindrical bushing or spacing members 134, one surrounding the stem of each bolt.

Referring now to the cradle support, the same 25 has a body member 52 and a bearing cap member 53 at each end of the body member. The body member may be in the form of an elongated rectangular block having a cavity between its ends for accommodating the lower portions 30 of the cradle and the roll carried thereby. The cap members 53 are secured in place by screws 59. Located within the openings at the opposite ends of the cradle support are roller bearing units, each of which may comprise an outer ring 48, 35 an inner ring 82, and roller bearings 85 interposed between the rings. The bottom surface of the cavity within the cradle support slopes towards a drain opening 60 through which moisture and other foreign material may drain from the 40 interior of the support.

The cradle support is mounted upon a plate 61 which rests upon and is secured to the bolsters or beams at the opposite sides of the truck frame. In the present illustrated disclosure, the cradle 45 support is mounted above, and extends generally longitudinally of, the beam or bolster 10, this arrangement being shown by way of illustration only. In order to support the cradle on and secure it to the truck frame without warping the 50 structure, the following arrangement is provided, reference being had to Fig. 5. The cradle support has, on its bottom and at one end, two supporting bosses 63 disposed at like distances to opposite sides of the medial longitudinal line of the 55 support, and the support has, at its other end, a medially positioned boss 64. These bosses give a three-bearing point support upon the truck frame. Four bolts 65, one located adjacent each corner of the cradle support, are provided for 60 securing the cradle support in place. Two of these bolts extend through the respective bosses 63. The bolts at the other end are disposed on opposite sides of the medial boss 64. These bolts extend through suitable openings in the bearing 65 caps 53, the body portion 52 of the cradle support, the plate 61, and the upper flanges of the bolster 10. On the lower end of each bolt is a clamp nut 66. The four bolts are not tightened up to such an extent as to cramp or warp the 70 structure but, on the other hand, the nuts are screwed up by hand and then the nuts are clamped against turning movement relative to the bolts.

Referring now to the cradle, the same comprises generally a rectangular hollow body portion

having end walls 74 and 75 and side walls 77 and 78. Extending from the end walls are aligned trunnions 80 and 81 which are positioned within the inner race rings 82 of the roller bearing units carried on the ends of the cradle support. Thus 5 it will be seen that the cradle support is mounted for oscillation about an axis which extends generally in the direction of the length of the track member 42, this axis, for convenience and terminology in claiming, being referred to as the 10 longitudinal axis.

In the present instance, the outer end of the journal bearings in the cradle support are closed by circular plates 88 secured in place by screws 89. The outer race or ring 48 is within two or 15 three-thousandths of an inch of fitting snugly between the plate 88 and the end wall of the cradle. The inner race terminates somewhat short of the plate 88. Disposed against the end wall of the cradle and positioned between the 20 inner and outer races is a hardened washer 90. Each of the trunnions 80 and 81 terminates short of the plates 88, thus leaving a cylindrical chamber, as indicated at 92. This chamber is used as a reservoir in which to store a supply of grease 25 which may flow to the rollers 85 through the space 94 provided between the plate 88 and the adjacent end of the inner race 82. As the opposite ends of the outer race 48 are closely adjacent to the plate 88 and the end wall of the carrier, 30 the grease will practically clog the journal at these points against taking in any grit.

Referring now to the main bearing roll 40, the same is preferably in the general nature of a sphere, two opposite sides of which have been 35 faced off along parallel planes. However, the radius of transverse curvature of the peripheral surface of the roll is materially less than the radius of the roll and is also less than the radius of transverse curvature of the trackway 137, and 40 the radius of transverse curvature of the trackway is less than the radius of the roll, all for a purpose hereinafter described more in detail. In Fig. 4, the radius of the roll is indicated by the radius line 95, the radius of transverse curvature of the roll by the radius line 96, and the radius of transverse curvature of the trackway 45 by the radius line 97.

The roll 40 is rotatably supported within the boxlike portion of the cradle by a bearing pin 50 or shaft 102 and tapered roller bearing units 107 and 108. The bearing pin has its ends located in bushings 100 and 101 located in aligned openings in the side walls 77 and 78 of the cradle. The axis of this shaft is disposed generally at right 55 angles to the axis of oscillation of the cradle and in the plane above the latter axis. In the drawings, the axis of the cradle is indicated as at a—a and the transverse axis of rotation of the roller at b—b.

Circular side plates 110, 111 are secured to the side walls 77 and 78 of the cradle by means of screws 113, and cover the ends of the pin 102 so as to prevent the latter from drifting longitudinally. Dowel pins, as indicated at 115, extend through each of these plates and into the pin 102 to restrain the pin from rotation relative to the cradle. The pin 102 is provided with an oil groove 117 extending from one end of the pin to past the center of the pin. A grease fitting 70 119 is secured to the plate 110 in communication with the groove 117 so that lubricant may be supplied to the tapered roller bearings 107 and 108. At the opposite ends of the tapered bearing units on which the roll is mounted are elastic 75

grease retaining plates, indicated at 140 and 141, which hug the opposite sides of the roll 40. These plates retain the lubricant within the roll and exclude foreign material from the tapered bearings.

Secured to the top of the cradle, as by means of screws 122 and binding strips 123, is a heavy layer or sheet of leather 120. The portion of this sheet immediately surrounding the top of the roll 40 is, as indicated at 126, cut out to permit the roll to project therethrough and engage the track member 42. Sewed, or otherwise secured, to the leather sheet at either side of the roll, is a piece of felt 128, portions of which rest upon and wipe the periphery of the roll adjacent the top center of the roll. These pieces of felt may be oiled with reasonable frequency in order to keep the roll at its area of contact with the track member 42 in lubricated condition. These felt members also serve as wipers.

From the foregoing description, taken in connection with the accompanying drawings, it will be understood that, as the truck and car body pivot relative to one another about the pivot pin 25, as would be the case when the car is going around a curve, for example, the track member 42 will ride longitudinally on the roll and, as this roll can turn about a transverse axis, there is substantially no friction between the roll and the track member during this movement. While the pivot between the truck and car body may be such as to substantially control relative vibrational movement sidewise between the car and truck, such movement cannot be entirely obviated. With my improved arrangement, such movement may be accommodated, while, at the same time, wear upon the parts of the side bearing, and particularly the roll, is practically eliminated. Upon sidewise relative movement between the truck and the car body, the cradle will oscillate about its axis, thus permitting the upper portion of the roll to swing sidewise, and, during such movement, the track member may roll sidewise on the periphery of the roll and, as this is a rolling action as distinguished from a sliding one, wear between these parts is eliminated. As the roll is journalled on the tapered bearings and the cradle is mounted for oscillation at its ends in bearing units, the several movements are substantially frictionless. With my improved arrangement, the wheel flanges may more readily accommodate themselves to the rails, shocks and jars are absorbed, and the riding qualities of the car improved. As previously pointed out, the oscillating center for transverse action of the roll, that is to say, the center *a*—*a* about which the cradle oscillates, is below the center of transverse curvature of the trackway 137 in which the roll tracks, and the distance between these centers is sufficiently great so as to insure that the main roll will maintain contact substantially with the central portion of the trackway, as otherwise the cradle would drift sideways until it found lodgment at one side or the other and thereby fail to properly function. Also, as pointed out, the radius of transverse curvature

of the roll is less than the radius of transverse curvature of the trackway, and the oscillating center of the cradle is below the center of rotation of the roll, relations which are of advantage in that they assist in maintaining the roll in engagement with the longitudinally center portion of the trackway and permit of a rolling action between the trackway and roll upon crosswise oscillation of the cradle and roll.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. A side bearing for railway cars comprising, a track member having a transversely curved trackway, a cradle mounted for oscillating movement about a longitudinal axis generally parallel to the length of said trackway, and a roll journaled in said cradle on an axis transverse to said first mentioned axis, said roll having its periphery transversely curved, and the radius of transverse curvature of said trackway being less than the distance between said longitudinal axis and said trackway.

2. A side bearing for railway cars comprising, a track member having a transversely curved trackway, a support below and extending generally parallel to said trackway, and a roll carried by said support for crosswise oscillating movement about a longitudinal axis and for rotation about a transverse axis, said roll having its periphery transversely curved, the radius of transverse curvature of said roll being less than that of said trackway and less than the radius of said roll, and said longitudinal axis being lower than said transverse axis.

3. A side bearing for supporting a car body upon a truck comprising, a track member having a transversely curved groove therein, a cradle support, a cradle supported by said cradle support for oscillation with respect thereto about an axis extending longitudinally thereof, and a roll carried by said cradle for rotation about an axis transverse to said above mentioned axis, the peripheral surface of said roll having a transverse curvature the radius of which is smaller than the radius of transverse curvature of said groove, and the axis of oscillation being spaced from said groove a distance greater than the radius of said roll so that said roll will roll across said groove when tilted about said first mentioned axis by movement of said car body transversely of said car truck.
